United States Patent Office.

FRANCIS M. ENGLISH, OF EVANSVILLE, INDIANA.

Letters Patent No. 100,513, dated March 8, 1870.

IMPROVED WASHING-MACHINE.

The Schedule referred to in these Letters Patent and making part of the same.

To all whom it may concern :

Be it known that I, Rev. FRANCIS M. ENGLISH, of Evansville, in the county of Vanderburgh, and State of Indiana, have invented a new and useful Improvement in Clothes-Washer; and I do hereby declare that the following is a full, clear, and exact description thereof, which will enable others skilled in the art to make and use the same, reference being had to the accompanying drawings forming part of this specification, in which—

Figure 1 is a top view of my improved washing-machine, the covers being removed.

Figure 2 is a view of one end of the machine.

Figure 3 is a view of the other end of the machine.

Figure 4 is a vertical cross-section of the same.

Similar letters of reference indicate corresponding parts.

My invention has for its object to furnish an improved machine which shall be so constructed as to wash the clothes and heat the water in which they are washed, which will do its work thoroughly and well, and without injury to even the most delicate fabrics, and which may be used with equal facility for various other purposes; and

It consists in the construction and combination of the various parts of the machine, as hereinafter more fully described.

A is the box or tub in which the washing is done, which is made semi-cylindrical in form, and with vertical ends, as shown in the drawings. The inner concave surface of the box or tub A may be made plane, corrugated, or ribbed, as may be desired.

B is the chamber or reservoir to receive the water to be heated, and which is extended around the outer or convex surface of the box or tub A in the form of a semi-annular chamber, as shown in figs. 2, 3, and 4.

The upper part of the chamber B may be enlarged upon one or both sides of the box or tub A, according to the amount of water desired to be heated at a time.

C is the furnace, which is placed beneath the water-reservoir or chamber B, its particular location being immaterial, and which is provided with a semi-annular flue, D, which extends around the outer or convex surface of the chamber B, and from which the smoke and other products of combustion enter the smoke-pipe or flue E.

The chamber B, furnace C, and flue D, equal in length the length of the machine, and the said furnace is provided upon its outer side for its entire length with a series or row of draught-openings, e', to make the combustion uniform throughout the entire length of the furnace.

F is a wheel, the inner surface of which has ribs or

wings, f', attached to it, as shown in figs. 1 and 4, and which is attached to the inner end of the short shaft G which passes out through a water-tight stuffing-box in one end of the box or tub A, and to the outer end of which is adjustably secured a large gear-wheel, H, by a set-screw passing through the hub and pressing against the projecting part of the said shaft G.

The teeth of the gear-wheel H mesh into the teeth of the small gear-wheel I attached to the end of the shaft J that revolves in bearings attached to the tub or box A, extends along the upper part of the rear side of the said tub or box A, and to its other end is attached a small gear-wheel, K, the teeth of which mesh into the teeth of the small gear-wheel k pivoted to the end of the box or tub A, and the teeth of which mesh into the teeth of the large gear-wheel L, the hub of which passes through, and works water-tight in the end of the box or tub A.

Through a square hole in the hub of the wheel L passes the square shaft M, to the outer end of which is attached the crank N, by means of which the machine is operated.

To the inner end of the shaft M is attached a rubber wheel, O, similar to the rubber wheel F, and provided with radial wings, ribs, or rubbers, o', in the same manner.

The small gear-wheel k may be pivoted to either end of the tub A, its object being simply to change the direction of motion so that the two rubber wheels F f' and O o' may be revolved in opposite directions.

By this construction, when the crank N is operated, the two rubber wheels F f' and O o' will be revolved in opposite directions, and will throw the water in which the clothes are placed between the said wheels into violent agitation, which will thus act upon the clothes in all their parts and effectually cleanse them, however much they may be soiled.

The boiler or water-heating chamber B is connected with the tub or box A by a bent pipe, P, which is provided with a stop-cock, Q, so that the hot water may be drawn from the boiler B into the tub A by simply turning the stop-cock Q.

The dirty water may be drawn from the tub A when desired by means of the stop-cock R connected with the lower part of said tub or box A.

The machine is supported upon legs S of such a length as to raise the machine to a convenient height.

Having thus described my invention,

I claim as new, and desire to secure by Letters Patent—

1. The combination of the semi-cylindrical box or tub A, and the vertical winged wheels F f' and O o' with each other, said wheels being so arranged as to be revolved in opposite directions at the same time

and by the same operation, substantially as herein shown and described, and for the purpose set forth.

2. The combination of the curved or semi-annular boiler or water-heating chamber B, with the semi-cylindrical box or tub A, and winged wheels F f' and O o', substantially as herein shown and described, and for the purpose set forth.

3. The combination of the furnace C, curved flue D, and smoke-pipe or flue E, with the curved boiler or water-heating chamber B, semi-circular box or tub A, and winged wheels F f' and O o', substantially as

herein shown and described, and for the purpose set forth.

4. The combination of the crank N, gearing H I J K k L, and shafts G J M, with the winged wheels F f' and O o', and semi-cylindrical box or tub A, substantially as herein shown and described, and for the purpose set forth.

REV. F. M. ENGLISH.
